UNITED STATES PATENT OFFICE.

THOMAS B. SHANAHAN, OF MANLIUS, NEW YORK.

TROLLEY-POLE RETRIEVER.

1,084,172.

Specification of Letters Patent.

Patented Jan. 13, 1914.

Application filed September 2, 1909. Serial No. 515,880.

To all whom it may concern:

Be it known that I, THOMAS B. SHANAHAN, of Manlius, in the county of Onondaga and State of New York, have invented a 5 certain new and useful Trolley-Pole Retriever, of which the following is a specification.

My invention has for its object the production of a trolley-pole retriever which is 10 particularly simple in construction and durable and efficient in use; and to this end it consists in the combinations and constructions hereinafter set forth and claimed.

In describing this invention, reference is 15 had to the accompanying drawing in which like characters designate corresponding parts in all the views.

Figure 1 is a longitudinal sectional view, 20 partly in elevation, of my trolley-pole retriever. Fig. 2 is a sectional view on a smaller scale, on line A—A, Fig. 1. Fig. 3 is a face view of the inner wall of the support or case, and the shifter carried thereby. Fig. 4 is an end view of the reel and the 25 movable locking member for the spring.

This trolley-pole retriever comprises generally a support, a reel for the trolley-pole rope, a spring for turning the reel to wind the rope thereon, the spring being normally 30 under tension and rotatable with the reel, and means for normally holding the spring under tension and from turning the reel, said means being shiftable out of its normal 35 position to connect the spring to the support and release the spring to turn the wheel.

The support 1 which may be of any desirable form, size and construction, is here shown as a hollow shell comprising an inner wall or base 2, and a cap 3 detachably secured to the wall or base 2 by any suitable 40 means, as screws 4. The support 1 is formed with an opening 5, Fig. 2, for the passage of the trolley-pole rope 6, and the wall or base 2 of the support is provided with any 45 desirable means adapted to be attached to the dashboard or other suitable part of the car.

As best seen in Fig. 1, the reel 7 is loosely mounted on a shaft 8 journaled in the support 1, as hereinafter described, said reel being formed with a peripheral wall, a web 9 between the opposite ends of the reel, and a hub 10 encircling the shaft 8 and projecting from one side of the web toward the 55 inner wall or base 2, the peripheral wall

having the trolley-pole rope 6 partly wound thereon; and the web 9, the hub 10 and the opposing portion of the peripheral wall forming an annular chamber within the reel. The spring 11 for winding the trolley-pole 60 rope 6 upon the reel 7 is arranged in said annular chamber within the reel and is coiled around the hub 10, the inner end of the spring 11 being suitably fixed, as by a rivet 12, to said hub. The outer end of the 65 spring 11 is suitably fixed, as by a rivet 13, to a holder or barrel 14 comprising a cylindrical flange, and a disk-shaped wall 15, the cylindrical flange loosely fitting the portion of the peripheral wall of the reel 7 surrounding the hub 10, and the wall 15 loosely 70 encircling the shaft 8 and having its outer face substantially coincident with the contiguous end face of the reel 7, and its inner face provided with a hub 16 abutting against 75 the hub 10.

The means for normally holding the spring under tension comprises a locking member 17, movable about the axis of the reel and also lengthwise of such axis and 80 the shaft 8, and here shown as a disk loosely mounted on the shaft 8 adjacent to the end wall 15 of the spring holder and the contiguous end face of the reel 7. This member 17 is slidably interlocked with the 85 spring holder 14, being here shown as formed with openings 18 which receive shoulders 19 projecting from the opposing surface of the holder. Said member 17 is also provided with notches extending in- 90 wardly from its peripheral edge and forming shoulders 20 for coacting alternately with shoulders 21 and 22 provided upon opposing faces of the reel 7, and the inner wall or base 2 of the support 1, the shoulders 95 20 being normally engaged with the shoulders 21 and being movable out of engagement with the shoulders 21 into engagement with the shoulders 22 when the member 17 is shifted to the right. The shoulders 19 100 are of greater length than the shoulders 21 or 22, so that said member 17 is engaged with the shoulders 19 when the shoulders 20 are engaged either with the shoulders 21 or the shoulders 22; and the shoulders 21 and 22 are preferably provided with inclined or cam faces coacting with walls of the notches forming the shoulders 20 for facilitating shifting of the member 17. When the member 17 is in its position assumed in Fig. 1 110

with its shoulders 20 engaged with the shoulders 21, the spring 11 rotates with the reel 7 and is normally held under tension without effecting any movement of the reel, but when 5 the member 17 has been moved axially to the right disengaging its shoulders 20 from the shoulders 21 and engaging the shoulders 20 and 22, the member 17 holds the outer end of the coiled spring 11 from movement with 10 the reel, and thereupon the spring 11 operates to turn the reel and wind the trolley-pole rope upon the peripheral wall of the reel.

As shown in Fig. 1, the locking member 15 17 is moved lengthwise of the shaft 8 by a shifter 23 arranged in axial alinement with the shaft 8 and journaled in the wall or base 2 and movable endwise relatively to said wall or base. This shifter 23 is formed with 20 a socket 24 extending inwardly from one end thereof and receiving the contiguous end of the shaft 8 which terminates short of the bottom 25 of the socket 24 and has a non-circular extremity 26 fitting a correspondingly-shaped portion of the socket 24. The shifter 23 is provided with segmental bearing faces 27 arranged diametrically opposite to each other, and with segmental spaces or cutouts between the opposing ends 25 of the faces 27. Cams 28 arranged on opposite sides of the axis of the shaft 8 and fixed to the wall or base 2 are normally engaged with the faces 27 by a spring 29 interposed between the bottom 25 of the socket 30 24 of the shifter and the contiguous end of the shaft 8. When the free end of the trolley-pole flies upwardly owing to the disengagement of the trolley from the wire, the shaft 8 is partially rotated with the reel 7, 35 by connections presently described, and upon such rotation of the shaft the shifter 23 rotates therewith carrying the faces 27 from their normal position in engagement with the high points of the cams 28 to a position 40 opposite to the low points thereof. During this partial rotation of the shifter 23, the spring 29 slides the shifter axially and the axial movement of the shifter moves the locking member 17 to the right, Fig. 1, and 45 disengages the shoulders 20 of the member 17 from the shoulders 21 of the reel 7 and engages said shoulders 20 with the shoulders 22 of the wall or base 2. Upon the reverse partial rotation of the shaft 8 and the 50 shifter 23 the faces 27 ride up the inclined surfaces of the cams 28, thus sliding the shifter to the left against the action of the spring 29, and moving the locking member 17 to the left and disengaging its shoulders 55 20 from the shoulders 22 and engaging said shoulders 20 with the shoulders 21 of the reel. It is thus apparent that the engagement of the shoulders 20 of the locking member 17 with the shoulders 22 of the wall 60 or base 2 is effected by the spring 29 thereby

avoiding liability of injury to said shoulders 20 and 22 when being engaged.

Preferably, the shifter 23 is connected to the locking member 17 by a lost motion, the end of the socket 24 of the shifter nearest the locking member 17, being here shown as provided with an enlargement 30 which receives a hub 31 provided on the opposing side of the member 17, the inner face 32 of the enlargement 30 being spaced apart from the end face of the hub 31, and the outer end of the enlargement 30 being provided with inwardly extending shoulders 33 which enter a circumferential groove 34 in the hub 31, this groove being of greater width than the shoulders 33. A spring 35 is arranged in the enlargement 30 around the shaft 8 and between the inner face of the enlargement and the opposing end face of the hub 31, the spring 35 serving to transmit motion 85 from the shifter for moving the member 17 to the left and thereby yieldingly forcing the shoulders 20 of the locking member into engagement with the shoulders 21 of the reel 7, and the lost motion or space between 90 the shoulders 33 and the opposite wall of the groove 34 permitting the shifter 23 to move relatively to the locking member a limited distance.

The spring 35 constitutes yielding means 95 for normally holding the locking member 17 in engagement with the reel 7, and the spring 29 acting on the shifter 23 constitutes additional yielding means for forcing the locking member 17 out of engagement 100 with the reel and into engagement with the support 2, the spring 29 being normally restrained from acting by the cams 28 coacting with the shifter. The power transmitting means between the disk 38 and the locking member 17 comprises a shaft 8, 105 spring 29 and shifter 23.

The means for connecting the reel 7 to the shaft 8 when the trolley carried by the trolley-pole is disengaged from the trolley 110 wire preferably consists of dogs 36 pivoted intermediate of their ends at 37 to the outer or left end face of the reel 7, corresponding ends of the dogs 36 being adapted to engage a disk 38 fixed to the shaft 8 and their 115 other ends being weighted and connected to springs 39 carried by the reel, these springs 39 normally holding the dogs out of engagement with the disk 38. The centrifugal force, due to the rapid rotation of the reel 120 7 by the upward impulse of the free end of the trolley-pole when the trolley is disengaged from the wire, throws the weighted ends of the dogs 36 outwardly and causes the opposite ends of said dogs to engage the 125 disk 38, whereupon the reel 7, the disk 38 and the shaft 8 revolve together.

The disk 38 is shown as formed separable from the shaft 8, as engaged with a bearing face 40 upon the opposing face of the cap 130

3 of the support 1 and as provided with hubs 41, 42 extending from opposite sides of the disk and fitting the shaft 8, the outer hub 41 being journaled in a bearing 43 in the cap 3 of the support 1 and the inner hub 42 abutting against the web 9 of the reel 7, and being fixed to the shaft 8 by a pin 44. A coiled spring 45 surrounds the inner hub 42 of the disk 38 and its opposite ends are respectively secured to said hub 42 and to the reel 7, this spring serving to rotate the reel 7 to take up the slack in the trolley-pole rope, due to the different levels of the trolley-wire.

15 My trolley-pole retriever is provided with a hand-lever 46 which is suitably fixed to the shaft 8, and is here shown as encircling the extremity of the outer hub 41 of the disk 38 and as held in position on such extremity 20 by a plate 47 and a screw 48 passed through the plate 47 into the end of the hub 41. The hand lever 46 provides means for enabling the operator to rotate the shaft 8 to move the locking member 17 into engagement 25 with the reel 7, and thus reset the shifter 23 and the locking member 17 in their normal position after the trolley-pole has been retrieved.

In operation the parts are normally in 30 the position shown in Fig. 1, and when the trolley leaves the wire, it springs upwardly rotating the reel 7 as the trolley rope unwinds. During such rotation the centrifugal pawls 36 are thrown into engagement 35 with the ratchet teeth of the disk 38 against the action of their springs 39 and the disk 38 partially rotated thereby until the cams 27 have been moved over the face of the cams 28 into such position that the spring 40 29 can move the member 23 outwardly axially positioning the cams 27 between the cams 28. The rotary movement of the disk 38 is transmitted to the shifter 23 through the shaft 8. The outward movement of the 45 shifter 23 by the spring 29 shifts the locking member 17 from its position shown in Fig. 1 in which it is engaged with the lugs 21 of the reel, into engagement with the lugs 22 of the support or case 1, thus anchoring 50 one end of the spring to the support, the other end of the spring being connected to the reel. The reel will hence be rotated by the spring 11 in the opposite direction to that in which it is rotated by the trolley 55 rope, thus moving the pawls 36 in a retrograde direction so that their springs 39 can return them to their normal position. During the movement of the reel by the spring 11, the disk 38 and shaft 8 and member 23 remain stationary. After the trolley 60 has been retrieved, the spring 11 is restored to its original tension by pulling on the trolley rope and unwinding the same from the reel sufficiently to permit the trolley to 65 touch the wire and have the usual amount

of slack. The shifter 23 and parts operated thereby may then be reset in their initial position by means of the lever 46.

What I claim is:

1. A trolley-pole retriever comprising a support, a reel for the trolley-pole rope, a coiled spring for turning the reel to wind the rope thereon, one end of the spring being fixed to the reel, and a member connected to the other end of the spring and normally 70 engaging the reel, said member being movable lengthwise of the axis of the reel out of engagement with the reel and into engagement with the support, substantially as and for the purpose specified. 75

2. A trolley-pole retriever comprising a support, a shaft carried by the support, a reel for the trolley-pole rope, the reel being loosely mounted on the shaft and being held from movement axially relatively to the 80 shaft, a spring for turning the reel to wind the rope thereon, the spring being connected to the reel and normally rotatable therewith, and a member movable about the axis of the shaft and connected to the spring, 85 the member normally engaging the reel and being movable axially of the shaft into engagement with the support, substantially as and for the purpose specified. 90

3. A trolley-pole retriever comprising a support, a reel for the trolley-pole rope, a spring for turning the reel to wind the rope thereon, the spring being connected to the reel and normally rotatable therewith, a member connected to the spring and normally 95 engaging the reel, and a spring for forcing the member out of engagement with the reel and into engagement with the support, substantially as and for the purpose set forth. 100

4. A trolley-pole retriever comprising a support, a reel for the trolley-pole rope, a spring for turning the reel to wind the rope thereon, the spring being connected to the reel and normally rotatable therewith, a member connected to the spring and normally 105 engaging the reel and shiftable out of engagement with the reel into engagement with the support, yielding means for holding the member in engagement with the reel, and additional yielding means for forcing the member out of engagement with the reel and into engagement with the support, and means operable by the unwinding action 110 of the trolley rope on the reel for controlling the operation of said additional yielding means, substantially as and for the purpose described. 115

5. A trolley-pole retriever comprising a support, a reel for the trolley-pole rope, a spring for turning the reel to wind the rope thereon, the spring having one end connected to the reel, a holder connected to the other end of the spring, and means for connecting the holder to the reel to rotate therewith 125 120 130

and for connecting the holder to the support, the spring, holder and means being arranged with their axis coincident with that of the reel and said means being shiftable axially into and out of engagement with holder and the support, substantially as and for the purpose specified.

6. A trolley-pole retriever comprising a support, a reel for the trolley-pole rope, a spring for turning the reel to wind the rope thereon, the spring having one end connected to the reel, a holder connected to the other end of the spring, and a member slidably interlocked with the holder and normally engaging the reel, said member being movable out of engagement with the reel and into engagement with the support, substantially as and for the purpose set forth.

7. A trolley-pole retriever comprising a support, a reel for the trolley-pole rope, the support and the reel having shoulders on opposing faces thereof, a spring for turning the reel to wind the rope thereon, the spring having one end connected to the reel, a holder connected to the other end of the spring and having a shoulder of greater length than one of the first-mentioned shoulders, and a member slidably mounted on the shoulder of the holder and having an engaging shoulder for engaging the first-mentioned shoulders and normally engaging the shoulder provided on the reel, said member being shiftable for moving its shoulder out of engagement with the shoulder of the reel into engagement with the shoulder of the support, substantially as and for the purpose described.

8. A trolley-pole retriever comprising a support, a shaft carried by the support, a reel for the trolley-pole rope, the reel being loosely mounted on the shaft and being held from movement axially relatively to the shaft, a spring for turning the reel to wind the rope thereon, one end of the spring being connected to the reel, a holder concentric with the shaft and connected to the other end of the spring, and a member concentric with the shaft and movable relatively thereto lengthwise of the axis of the shaft, the member being locked from movement about the shaft relatively to the holder, and said member normally engaging the reel and being movable axially of the shaft into engagement with the support, substantially as and for the purpose specified.

9. A trolley-pole retriever comprising a support, a shaft carried by the support, a reel for the trolley-pole rope, the reel being loosely mounted on the shaft and being held from movement axially relatively to the shaft, a spring, one end of the spring being connected to the reel, a holder concentric with the shaft and connected to the other end of the spring, a member concentric with

the shaft and movable relatively thereto lengthwise of the axis of the shaft, the member being locked from movement about the shaft relatively to the holder, and said member normally engaging the reel and being movable axially of the shaft into engagement with the support, yielding means for normally holding the member in engagement with the reel, additional yielding means for forcing the member out of engagement with the reel and into engagement with the support, means for normally restraining the operation of the additional yielding means, and means for moving the additional yielding means out of its operative relation with its restraining means including means operated by the reel when turning under the impulse of the unwinding trolley rope, substantially as and for the purpose set forth.

10. A trolley-pole retriever comprising a support, a reel for the trolley-pole rope, a spring for turning the reel to wind the rope thereon, the spring being connected to the reel and normally rotatable therewith, a member connected to the spring and normally engaging the reel, said member being movable out of engagement with the reel and into engagement with the support, a shifter connected to the member and movable about the axis of the reel and lengthwise of said axis, means for forcing the shifter axially in one direction as the shifter turns about its axis, and means for forcing the shifter axially in the opposite direction as the shifter turns in the reverse direction, substantially as and for the purpose described.

11. A trolley-pole retriever comprising a support, a reel for the trolley-pole rope, a spring for turning the reel to wind the rope thereon, the spring being connected to the reel and normally rotatable therewith, a member connected to the spring and normally engaging the reel, said member being movable out of engagement with the reel and into engagement with the support, a shifter connected to the member with a lost motion and movable about the axis of the reel and lengthwise of said axis, means for taking up the lost motion between the member and the shifter, a cam for forcing the shifter axially in one direction as the shifter turns about its axis, and a spring for forcing the shifter axially in the opposite direction as the shifter turns in the reverse direction, substantially as and for the purpose specified.

12. A trolley-pole retriever comprising a support, a reel for the trolley-pole rope, a spring for turning the reel to wind the rope thereon, the spring being connected to the reel and normally rotatable therewith, a member connected to the spring and normally engaging the reel, said member being movable out of engagement with the reel, and into engagement with the support, a

shifter connected to the member with a lost motion and movable about the axis of the reel and lengthwise of said axis, said member and shifter having internal opposing faces spaced apart from each other, a coiled spring between said opposing faces of the member and the shifter, a cam for forcing the shifter axially in one direction as the shifter turns about its axis, and a spring for forcing the shifter axially in the opposite direction as the shifter turns in the reverse direction, substantially as and for the purpose set forth.

13. A trolley-pole retriever comprising a support, a shaft carried by the support, a reel for the trolley-pole rope, the reel being loosely mounted on the shaft, a spring for turning the reel to wind the rope thereon, the spring being connected to the reel and normally rotatable therewith, a member connected to the spring and normally engaging the reel, said member being movable out of engagement with the reel and into engagement with the support, a shifter connected to the member and arranged in axial alinement with the shaft, the shifter being movable with the shaft about the axis thereof and being movable relatively to the shaft lengthwise of said axis, means for forcing the shifter axially in one direction as the shifter turns about its axis, and means for forcing the shifter axially in the opposite direction as the shifter turns in the reverse direction, substantially as and for the purpose described.

14. A trolley-pole retriever comprising a support, a shaft carried by the support, a reel for the trolley-pole rope, the reel being loosely mounted on the shaft, a spring for turning the reel to wind the rope thereon, the spring being connected to the reel and normally rotatable therewith, a member connected to the spring and normally engaging the reel, said member being movable out of engagement with the reel and into engagement with the support, a shifter connected to the member and arranged in axial alinement with the shaft and formed with a lengthwise socket opening through one end thereof for receiving one end of the shaft, the shaft terminating short of the bottom of the socket, the shifter being movable with the shaft about the axis thereof and being movable relatively to the shaft lengthwise of such axis, a cam for forcing the shifter axially in one direction as the shifter turns about its axis, and a spring between the end of the shaft and the bottom of the socket for forcing the shifter axially in the opposite direction as the shifter turns in the reverse direction, substantially as and for the purpose specified.

15. A trolley-pole retriever comprising a support, a shaft carried by the support, a reel for the trolley-pole rope, the reel being

loosely mounted on the shaft, a spring for turning the reel to wind the rope thereon, the spring being connected to the reel and normally rotatable therewith, a member connected to the spring and normally engaging the reel, said member being movable out of engagement with the reel and into engagement with the support, a shifter connected to the member with a lost motion, the shifter being movable with the shaft about the axis thereof and being movable relatively to the shaft lengthwise of such axis, yielding means for taking up the lost motion between the member and the shifter, means for forcing the shifter axially in one direction as the shifter turns about its axis, and yielding means for forcing the shifter axially in the opposite direction as the shifter turns in the reverse direction, substantially as and for the purpose set forth.

16. A trolley pole retriever comprising a support, a rotatable shaft carried by the support, a reel loosely mounted on the shaft, a spring for actuating the reel in one direction to retrieve the trolley, the spring being connected at one end to the reel, a shiftable anchor member having a hub loosely mounted on the shaft and normally interlocking with the reel to rotate therewith and being shiftable into interlocking engagement with the support, the anchor member being connected to the other end of the spring, means operated by the free rotation of the reel on the shaft for shifting the anchor member into engagement with the support, said means comprising a centrifugal part movable into connection with the shaft to rotate the same in one direction, a shifter formed with a socket for receiving one end of the shaft, the shifter being journaled in the support and rotatable with the shaft and slidably axially thereof, and said shifter and the hub of the anchor member being coupled together by lost motion, a compression spring interposed between the anchor member and the shifter, a compression spring interposed between the end of the shaft and the bottom of the socket of the shifter, fixed cams on the support normally coacting with the shifter for holding the shifter in position to compress the compression springs and operating to permit said springs to extend during partial rotation of the shaft by the centrifugal means, in order to permit the anchor member to shift into engagement with the support, and manual means for turning the shaft to reset the shifter, substantially as and for the purpose described.

17. A trolley-pole retriever comprising a support, a shaft having one end journaled in the support, a reel for the trolley-pole rope, the reel being loosely mounted on the shaft, a spring for turning the reel to wind

the rope thereon, the spring being connected to the reel and normally rotatable therewith, a member connected to the spring and normally engaging the reel, said member being movable out of engagement with the reel and into engagement with the support, a shifter connected to the member and arranged in axial alinement with the shaft, the shifter being journaled in the support and forming a support for the other end of the shaft, and means for moving the shifter axially in opposite directions, substantially as and for the purpose specified.

18. A trolley-pole retriever comprising a support, a shaft having one end journaled in the support, a reel for the trolley-pole rope, the reel being loosely mounted on the shaft, a spring for turning the reel to wind the rope thereon, the spring being connected to the reel and normally rotatable therewith, a member connected to the spring and normally engaging the reel, said member being movable out of engagement with the reel and into engagement with the support, a shifter connected to the member and arranged in axial alinement with the shaft and formed with a lengthwise socket opening through one end thereof for receiving one end of the shaft, the shaft terminating short of the bottom of the socket, the shifter being journaled in the support and forming a support for the other end of the shaft, and the shifter being movable with the shaft about the axis thereof and being movable relatively to the shaft lengthwise of such axis, a cam for forcing the shifter axially in one direction as the shifter turns about its axis, and a spring between the end of the shaft and the bottom of the socket for forcing the shifter axially in the opposite direction as the shifter turns in the reverse direction, substantially as and for the purpose set forth.

19. A trolley-pole retriever comprising a support, a shaft having one end journaled in the support, a reel for the trolley-pole rope, the reel being loosely mounted on the shaft, a spring for turning the reel to wind the rope thereon, the spring being connected to the reel and normally rotatable therewith, a member connected to the spring and normally engaging the reel, said member being movable out of engagement with the reel and into engagement with the support, a shifter connected to the member with a lost motion, the shifter being journaled in the support and forming a support for the other end of the shaft, and the shifter being movable with the shaft about the axis thereof and being movable relatively to the shaft lengthwise of such axis, a spring for taking up the lost motion between the member and the shifter, a cam for forcing the shifter axially in one direction as the shifter turns about its axis, and a spring for forc-

ing the shifter axially in the opposite direction as the shifter turns in the reverse direction, substantially as and for the purpose described.

20. A trolley-pole retriever comprising a support, a disk journaled in the support, a reel for the trolley-pole rope, the reel being movable relatively to the disk, means carried by the reel for coacting with the disk and operable to connect the reel and disk to rotate together in one direction, a spring for turning the reel to wind the rope thereon, the spring being connected to the reel and normally rotatable therewith, a member connected to the spring and normally engaging the reel, said member being movable out of engagement with the reel and into engagement with the support, and power-transmitting means between the disk and said member for shifting said member out of engagement with the reel and anchoring the same to the support for permitting the spring to act to turn the reel in the opposite direction, substantially as and for the purpose specified.

21. A trolley-pole retriever comprising a support, a disk journaled in the support, a reel for the trolley-pole rope, the reel being movable relatively to the disk, means pivoted to the reel for coacting with the disk and operable to connect the reel and disk to rotate together in one direction, a coiled spring for turning the reel to wind the rope thereon, one end of the spring being fixed to the reel, a member connected to the other end of the spring and normally engaging the reel, said member being movable out of engagement with the reel and into engagement with the support, and power-transmitting means between the disk and said member for shifting said member out of engagement with the reel and anchoring the same to the support when the first-mentioned means is operated to engage the disk, substantially as and for the purpose set forth.

22. A trolley-pole retriever comprising a support, a shaft having one end journaled in the support and provided with a disk, a reel for the trolley-pole rope, the reel being loosely mounted on the shaft, centrifugal means pivoted to the reel for coacting with the disk and operable to connect the reel and disk to rotate together in one direction, a spring for turning the reel to wind the rope thereon, the spring being connected to the reel and normally rotatable therewith, a member connected to the spring and normally engaging the reel and rotatable therewith, said member being movable out of engagement with the reel and into engagement with the support to anchor one end of the spring to the support, a shifter connected to the member and arranged in axial alinement with the shaft, the shifter being journaled in the support and forming

a support for the other end of the shaft, and being connected to the shaft to rotate therewith and slide axially thereof, a cam for normally holding the shifter to position 5 said member in engagement with the reel, the rotation of the shaft and shifter through the centrifugal means acting to position the shifter and cam to permit the shifter to move and carry said member out of engagement with the reel and anchor the same to 10 the support, and manual means for turning the shaft to reset the shifter in its normal

relation with said cam, substantially as and for the purpose described.

In testimony whereof, I have hereunto 15 signed my name in the presence of two attesting witnesses, at Syracuse, in the county of Onondaga, in the State of New York, this 30th day of August, 1909.

THOMAS B. SHANAHAN.
